US0D1084254S

(12) **United States Design Patent** (10) **Patent No.:** **US D1,084,254 S**
(45) **Date of Patent:** **** Jul. 15, 2025**

(54) **TOILET SEAT**

(71) Applicant: **Kohler Co.**, Kohler, WI (US)

(72) Inventor: **Erich D. Slothower**, Mill Valley, CA (US)

(73) Assignee: **Kohler Co.**, Kohler, WI (US)

(**) Term: **15 Years**

(21) Appl. No.: **29/932,030**

(22) Filed: **Mar. 11, 2024**

Related U.S. Application Data

(62) Division of application No. 29/851,767, filed on Aug. 31, 2022, now Pat. No. Des. 1,024,294, which is a division of application No. 29/724,160, filed on Feb. 13, 2020, now Pat. No. Des. 969,281.

(57) **CLAIM**

The ornamental design for a toilet seat as shown and described.

DESCRIPTION

FIG. 1 is a perspective view of another embodiment of the claimed design;

FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1;

FIG. 7 is a bottom view of the claimed design shown in FIG. 1;

FIG. 8 is a perspective view of another embodiment of the claimed design;

FIG. 9 is a front view of the claimed design shown in FIG. 8;

FIG. 10 is a rear view of the claimed design shown in FIG. 8;

FIG. 11 is a side view of the claimed design shown in FIG. 8;

FIG. 12 is another side view of the claimed design shown in FIG. 8;

FIG. 13 is a top view of the claimed design shown in FIG. 8; and,

FIG. 14 is a bottom view of the claimed design shown in FIG. 8.

The broken lines shown in the drawings represent portion of the toilet seat that form no part of the claimed design. The dash dot broken lines shown in the drawings depict boundaries of the claim and form no part thereof.

1 Claim, 10 Drawing Sheets
